UNITED STATES PATENT OFFICE.

LEWIS E. MORRISON, OF PHILADELPHIA, PENNSYLVANIA.

TRIPPING MECHANISM FOR PRINTING-PRESSES.

No. 818,803.

Specification of Letters Patent.

Patented April 24, 1906.

Application filed September 29, 1904. Serial No. 226,508.

To all whom it may concern:

Be it known that I, LEWIS E. MORRISON, a citizen of the United States, residing at Philadelphia, in the county of Philadelphia and 5 State of Pennsylvania, have invented a new and useful Tripping Mechanism for Printing-Presses, of which the following is a specification.

This invention relates to a tripping mechanism for preventing the operation of a printing-press except when a sheet of paper has been supplied to the press.

The object of this invention is to provide a strong, simple, and efficient automatic tripping mechanism which will insure a simple, direct, and automatic control of a printing mechanism from the sheet of paper which is about to be printed.

To this end this invention consists of a 20 tripping mechanism for printing-presses and of the combinations of parts therewith, as hereinafter described, and more particularly pointed out in the claims at the end of this specification.

25 In the accompanying two sheets of drawings, Figure 1 is a side view of sufficient parts of a job-printing press to illustrate the application of my invention thereto. Fig. 2 is a detail view of the connections operated by 30 the feeding of a sheet of paper to the press, and Fig. 3 is an enlarged detail view of the same. Fig. 4 is a view of the eccentric piece.

A tripping mechanism constructed according to this invention has been especially designed for use on job-printing presses. In using the ordinary bed-and-platen printing-presses it is now the usual practice to feed the presses by hand. One serious objection to the use of automatic feeders in connection 40 with job-printing presses is due to the fact that if for any reason the automatic feeder should fail to operate or the supply of sheets should become exhausted the printing-form would be repeatedly carried up against the platen, spoiling the impression-sheet and the underlays by means of which the surface of the platen has been made ready for printing any particular form.

The especial object of the present invention is to provide a tripping mechanism which will automatically prevent the printing operation of a bed-and-platen or other printing-press except at such times as a sheet has been fed to the press.

55 Referring to the accompanying drawings for a detail description of an apparatus em-

bodying this invention, 10 designates one of the side frames of a bed-and-platen printing-press. Mounted upon the side frames is a platen 11 for receiving the impression from a 60 form of type mounted on the type-bed 13, which type-bed 13 is carried by the swinging frame 12. These parts may be of any of the usual or preferred constructions employed in bed-and-platen printing-presses. Carried by 65 the side frames 10 is a sheet-feeding mechanism 14, which is intended to automatically supply sheets to the registering-table 15. The automatic sheet - supplying mechanism 14 may be of the ordinary or approved construc- 70 tions and need not be herein described at length, the successive sheets supplied from the feed mechanism 14 being preferably fed over the registering-table by fingers or feed- 75 ing devices engaging the rear edges of suc- cessive sheets. Coöperating with the regis- 80 tering-table 15 I provide connections which are controlled by the passage of successive sheets for preventing the printing action of the press except at a time when a sheet has been fed to the press.

The operating connections for the printing mechanism, as herein illustrated, comprise the main gear or crank wheel 16, having a crank-pin which receives one end of the link 85 17. At its other end the link 17 is connected to an eccentric piece 17^a, having an operating-arm 18. When the eccentric piece is in normal position, (illustrated in Fig. 1,) the link 17 will swing the type-bed up to full 90 printing position, so that a type formed thereon will be moved up into printing en- 95 gagement with the stationary platen. When, however, the eccentric piece is shifted from the position illustrated in Fig. 1, the length 100 of the connection between the swinging frame, which carries the type-bed, and the crank-wheel which operates the same will be increased, so that a type-form upon the type- 105 bed will be moved up adjacent to but not into contact with the platen. To set the ec- 110 centric piece so as to prevent printing action from taking place except when a sheet has been fed to the press, I employ a pivoted arm 19, having a roller 20 near its upper end, which roller 20 is located in position to be en- gaged by the arm 18 of the eccentric piece. At its lower end the swinging arm 19 is con- 115 nected by a spring-pressed rod 21 to a rock- arm 22, which turns with the swing-frame 12, that carries the type-bed. By means of this construction when the pivoted arm 19 is left

free or unlocked said arm 19 will move forward simultaneously with the type-bed and its roller 20 will be moved out of the path of the arm 18. When the arm 19 is locked, so 5 as to be prevented from moving forward, the roller 19 will remain in the path of the arm 18 and a printing action will be prevented. The spring on the rod 21 provides the necessary lost motion when the arm 19 is locked 10 against forward movement. The locking means which I employ for holding the pivoted arm 19 stationary when a sheet has not been fed to the press comprise the sliding arm 23 and a catch 24 coöperating therewith. The catch 24 is lifted up out of the way of the sliding piece 23 whenever a sheet is fed to the press. The connections for doing this are most clearly illustrated in Figs. 2 and 3. As shown in these figures, the cross- 15 rod R is provided with a support near its center for receiving the sliding piece, carrying a contact-wheel 26 at its lower end. The contact-wheel 26 coöperates with the registering-table 15, so as to be turned by the passage of a sheet upon the registering-table. Turning with the contact-wheel 26 is a small pulley having a tape 27 secured thereto. The other end of the tape 27 is wound on a small pulley carried by a spring-pressed shaft 28. 20 At its other end the spring-pressed shaft 28 is connected to a tape 25 for lifting the catch 24. The tapes 25 and 27 are wound in opposite directions upon the shaft 28, and by means of this construction when the roll 26 25 unwinds the tape 27 from its shaft 28 it serves to wind up the tape 25 and lift the catch 24. By means of these connections the passage of a sheet along the registering-table 15 releases the tripping mechanism, so 30 that an impression will be made by the type-form. In order to insure a perfect coöperation of the pressure-roller 26 with the table 15, I provide the rod 23 with a downwardly-extending finger or projection 23^a near its 35 end for engaging a plate P, carried by a bell-crank lever pivoted at 29. At its upper end the bell-crank lever is connected by a link 30 to the downwardly-extending arm of a bell-crank lever 31, which engages and forces 40 down the slide carrying the roll 26.

I am aware that numerous changes may be made in practicing my invention by those who are skilled in the art without departing from the scope of my invention as expressed 45 in the claims and also that my tripping mechanism may be applied to different types of presses from the bed-and-platen job-printing press which I have herein shown and described. I do not wish, therefore, to be limited to this particular construction, but

What I do claim, and desire to secure by Letters Patent of the United States, is—

1. In a printing-press the combination of its two members, namely the platen and 55 type-bed, means for operating one of the

members, an eccentric piece for shifting the pivotal connection between the movable member and its operating means, a stop for operating the eccentric piece, a lock for said stop comprising a sliding rod, a latch and 70 connections for releasing the latch by feeding a sheet to the press.

2. In a printing-press, the combination of the platen, the movable type-bed, means for operating the type-bed, an eccentric piece 75 for shifting the pivotal connection between the type-bed and its operating means, a stop for operating the eccentric piece, a lock for said stop comprising a sliding rod, a latch and 80 connections for releasing the latch by feeding a sheet to the press.

3. In a printing-press, the combination of the platen, the movable type-bed, a link for operating the type-bed, an eccentric piece connecting the link with the type-bed, a stop 85 for operating the eccentric piece, a lock for said stop comprising a sliding rod, a latch and connections for releasing the latch by feeding a sheet to the press

4. In a printing-press, the combination of 90 the platen, the movable type-bed, a link for operating the type-bed, an eccentric piece with an extended arm connecting the link with the type-bed, a stop for operating the eccentric piece, a lock for said stop comprising a sliding rod, a latch and 95 connections for releasing the latch by feeding a sheet to the press.

5. In a printing-press, the combination of 100 the platen, the movable type-bed, an operating-link, an eccentric piece with an extended arm connecting the operating-link and type-bed, a stop for turning the eccentric piece, connections for normally moving the stop out of operative position, and a lock for said 105 stop comprising a sliding rod, a latch and connections for releasing the latch by feeding a sheet to the press.

6. In a printing-press, the combination of 110 the platen, the movable type-bed, an operating-link, an eccentric piece connecting the operating-link and type-bed, a stop for turning the eccentric piece, connections for normally moving the stop out of operative position, and a lock for said 115 stop comprising a sliding rod, a latch and connections for releasing the latch by feeding a sheet to the press.

7. In a printing-press, the combination of 120 the platen, the movable type-bed, a stop for preventing the printing operation of the type-bed, and means controlled by feeding a sheet of paper to the press for releasing the stop comprising a contact-wheel engaging the sheet of paper, and means operated by the contact-wheel for moving the stop.

8. In a printing-press, the combination of 125 the platen, the movable type-bed, a stop for preventing the printing operation of the type-bed, and means controlled by feeding a sheet of paper to the press for releasing the 130

stop comprising a contact-wheel engaging the sheet of paper, a spring-pressed shaft, a tape adapted to be unwound from the shaft by the contact-wheel, and a tape adapted to 5 wind up on the shaft to move the stop.

9. In a printing-press, the combination of the platen, the movable type-bed, a stop for preventing the printing operation of the type-bed, means controlled by feeding a 10 sheet of paper to the press for releasing the stop comprising a contact-wheel engaged by the sheet of paper, and connections from the contact-wheel for moving the stop and means for automatically pressing the contact-wheel 15 into position to be engaged by a succeeding sheet.

10. In a printing-press, the combination of the platen, the movable type-bed, an operating-link, an eccentric piece connecting the 20 operating-link and type-bed, a stop for turning the eccentric piece, connections for normally moving the stop out of operative position, a lock for said stop comprising a sliding rod, and a latch coöperating therewith, and 25 means controlled by feeding a sheet to the press for releasing the latch comprising a

contact-wheel engaged by the sheet, and connections from the contact-wheel for moving the latch.

11. In a printing-press, the combination of 30 the platen, the movable type-bed, an operating-link, an eccentric piece connecting the operating-link and type-bed, a stop for turning the eccentric piece, connections for normally moving the stop out of operative position, a lock for said stop comprising a sliding rod and a latch, connections for releasing the latch by feeding a sheet of paper to the press comprising a contact-wheel engaging the sheet of paper, a spring-pressed shaft, a tape 35 adapted to be unwound from the shaft by the contact-wheel and a tape adapted to wind up on the shaft to move the latch, and means for pressing the contact-wheel into position to be engaged by the succeeding sheet. 40

In testimony whereof I have hereunto set my hand in the presence of two subscribing witnesses.

LEWIS E. MORRISON.
